UNITED STATES PATENT OFFICE.

GUSTAVUS H. ZSCHECH, OF INDIANAPOLIS, INDIANA, ASSIGNOR TO ROSA MILLER, OF SAME PLACE.

SAW-CATCHER FOR BAND-SAW MILLS.

SPECIFICATION forming part of Letters Patent No. 356,220, dated January 18, 1887.

Application filed April 22, 1886. Serial No. 199,762. (No model.)

To all whom it may concern:

Be it known that I, GUSTAVUS H. ZSCHECH, a citizen of the United States, residing at Indianapolis, in the county of Marion and State 5 of Indiana, have invented certain new and useful Improvements in Saw-Catchers for Band-Saw Mills; and I do declare the following to be a full, clear, and exact description of the invention, such as will enable others skilled 10 in the art to which it appertains to make and use the same, reference being had to the accompanying drawings, and to the letters and figures of reference marked thereon, which form a part of this specification.

15 My invention relates to a saw-catcher for a band sawing-machine, the object thereof being to provide a device for catching the saw when, through accident, breakage, or any other cause, it is thrown from the saw-wheel while 20 in motion; and the invention consists in the construction, arrangement, and combination of parts, as will be hereinafter fully set forth.

In the annexed drawings, illustrating my invention, Figure 1 is a front elevation of my 25 improved device for catching saws, and shows also the rim of the saw-wheel. Fig. 2 is an end elevation of the same. Fig. 3 is a top plan view, and Fig. 4 is a detail cross section, of the saw-catcher through one of its rollers.

30 Like letters of reference designate like parts in the several figures.

B represents the upper band-saw wheel, which is suitably journaled in the frame, one end of its journal or shaft entering the column 35 A, while the other end is upheld by the out-hanging journal-box arm G. A semicircular rim, C, somewhat less in diameter than that of the band-wheel and provided with a radial series of spokes, D, secured to said rim, and 40 also to a central hub, E, is situated in close proximity to the band-wheel. The center of the hub E of this semicircular wheel is firmly secured to the journal-box arm G by screws or bolts, and the rim C is concentric with the 45 band-wheel, and is preferably made of flat bar-iron bent into the required shape.

The rim C of the saw-catching device is provided on its outer surface with a series of transverse rollers, F, mounted each in a stand,

a, which is made fast to the rim C by rivets 50 or other suitable means. These stands a are also so constructed as to have journaled therein not only the horizontal roller F, but a second roller, H, situated at right angles to the roller F. There may be any number of these roller 55 devices situated a greater or less distance apart throughout the length of the semicircular rim, and when it is so desired the construction may be so modified as to dispense with the secondary rollers H, and provide in lieu thereof a 60 flange, b, (see Fig. 4,) which will likewise be perpendicular to the roller F, and which may be made in sections—that is, one part for each roller, and none in the intervening space between the rollers; or the flange b may be a 65 continuous semicircular strip secured to each stand a. These rollers are preferably made of wood and furnished with iron gudgeons, which are fitted into suitable journal-holes in the stands a. 70

It will be evident from the foregoing description of the construction of the parts how the device will operate in actual practice. The inner extremities of the rollers F are located close to the band-saw. When, therefore, the saw, during its revolution at a high rate of speed, happens from any cause to be thrown from the wheel, it will be caught by the rollers F, upon which it will continue its revolving motion, without any violent or sudden resistance, until at length the frictional contact with the rollers causes it to stop. The stoppage of the saw is gradual, therefore. Were the saw to be thrown upon a dead surface, there would be such a sudden resistance 85 to its motion as to likely cause it to buckle up and break; but in my improved device, wherein a series of rollers receive the saw, this danger is obviated. The accessory rollers H or their equivalent—the flange b—serve to 90 keep the saw from falling or slipping off the catcher.

Having thus described my invention, what I claim as new, and desire to secure by Letters Patent, is—

1. The combination, with a band-saw wheel, of an adjacent stationary rim concentric with the wheel and provided with a series of trans-

verse rollers journaled in suitable stands upon the rim, substantially as shown, and for the purpose set forth.

2. A saw-catcher for band-saw mills, consisting of a semicircular rim located close to the upper band-saw wheel and a series of roller devices secured at intervals upon the rim, each of said devices consisting of a stand, in which is journaled a roller transverse to the rim, and a second roller at right angles to the first, substantially as shown and described.

3. A saw-catcher for band-saw mills, consisting of a semicircular rim located close to and concentric with the upper band-saw wheel, 15 a series of transverse rollers journaled in stands upon the rim, and a series of rollers or guards perpendicular to those of the first series, substantially as described.

4. In a saw-catcher for band-saws, the combination of the rim C, spokes D, and hub E, 20 rigidly mounted upon a support, and a series of rollers, F, journaled in stands a, secured to the rim, as specified and shown.

5. The combination of the rim C, the stands a, secured thereto, the rollers F, journaled in 25 the stands and transverse to the rim, and the rollers or guards H, likewise journaled in the stands a, and at right angles to the rollers F, all arranged substantially as shown and described.

In testimony whereof I affix my signature in presence of two witnesses.

GUSTAVUS H. ZSCHECH.
